His Attorney

UNITED STATES PATENT OFFICE

GEORGE W. BAUGHMAN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed September 24, 1929. Serial No. 394,792.

My invention relates to railway traffic controlling apparatus, and particularly to continuous inductive train control systems of the code type. In systems of this character, the code transmitter is usually normally de-energized, and is set into operation when the track relay is de-energized due to a train entering the section. It follows that the code transmitter should be set into operation as promptly as possible when a train enters the section, and it is usually the release time of the track relay which determines the interval of time between the entrance of the train and the starting of the code transmitter. Direct current track relays, and track relays of the alternating current centrifugal type, both require an appreciable interval of time for release after the relay becomes de-energized due to the entrance of the train into the section, and one feature of my invention is the provision of means for setting the code transmitter into operation before the track relay actually releases, thereby eliminating the possibility of a flip of the cab signal.

I will describe two forms of apparatus embodying my invention, and will then point out the novel features thereof in claims.

In the accompanying drawing, Fig. 1 is a diagrammatic view showing one form of apparatus embodying my invention applicable for use with direct current track circuits. Fig. 2 is a view similar to Fig. 1, but showing a modification of my invention applicable to alternating current track circuits.

Similar reference characters refer to similar parts in each of the views.

Referring first to Fig. 1, the reference characters 1 and 1^a designate the track rails of a stretch of railway track along which traffic normally moves in the direction indicated by the arrow. These rails are divided by insulated joints 2 to form track sections, of which only one complete section E—F is shown in the drawing.

Section E—F is provided with a track circuit comprising a track battery 3 connected across the rails at the exit end of the block (through the secondary of a transformer A hereinafter described), and a track relay R^E

connected across the rails at the entrance end of the section.

Alternating train governing current is supplied to the rails of section E—F from a transformer 5, the primary of which is connected with a source of alternating current which is not shown in the drawing. The secondary of transformer 5 is at times connected with a motor M, which drives a code transmitter T comprising a contact 14 which is periodically closed while the transmitter is in operation. When the transmitter T is in operation, alternating current is supplied from the transformer 5 to the primary of transformer A through the contact 14 provided that track relay R^E for the section next in advance is energized. The circuit for the motor M and the circuit for the primary of transformer A are controlled by front contacts 7 and 8 of a normally de-energized code relay D. The code relay D is provided with a circuit which passes from terminal B of a suitable source of current, through back contact 6 of track relay R^E, and the winding of the relay D to terminal C of the same source of current. It follows that relay D is normally de-energized, but will be energized when track relay R^E is open due to the presence of a train in section E—F. When relay D becomes energized, an operating circuit for the motor M will become closed, which circuit includes the secondary of transformer 5 and front contact 7 of relay D. At the same time, a circuit for the primary of transformer A will become closed, which circuit includes the secondary of transformer 5, front contact 8 of relay D, contact 14 of the code transmitter T, and front contact 9 of track relay R^E. It follows that if track relay R^E is energized, alternating train governing current will be periodically supplied to the rails of section E—F through transformer A.

The circuit for the code relay D is provided with a branch around back contact 6 of track relay R^E, which branch includes a polar contact 10 of a polarized relay X. The winding of this relay is connected with the secondary of a transformer 4, the primary of which is interposed in the connection between the track relay R^E and track rail 1,

Relay X is characterized by the fact that after the relay becomes de-energized, its polarized armature remains in the position to which it was last moved. This relay is so connected in the track circuit that a decrease of the current in the primary of transformer 4, induces a current in the secondary which causes the polar contact 10 to be shifted to the right, whereas an increase of the current in the primary of transformer 4 causes this polar contact to be shifted to the left.

The operation of the apparatus shown in Fig. 1 is as follows: Normally the circuit for the code relay D is open at both contacts 6 and 10 of relays R^E and X. When a train enters section E—F it will shunt track relay R^E, thereby decreasing the amount of current supplied to the transformer 4, so that the polar contact 10 of relay X will immediately swing to the right to close the circuit for code relay D. This operation of contact 10 will occur before the back contact 6 of relay R^E becomes closed, so that the time between the entrance of the train into the section and the energization of code relay D is reduced to a minimum. When the train leaves section E—F, the amount of current supplied to relay R^E and the primary of transformer 4 will increase so that relays R^E and X will be operated to open both contacts 6 and 10, the operation of the code transmitter will then cease.

Referring now to Fig. 2, the apparatus is similar to that shown in Fig. 1, except that the track battery is omitted, and alternating track circuit current is normally supplied to transformer A from the secondary of transformer 5 through a back point of contact 8 of the code relay D. When code relay D becomes energized, however, the continuous supply of alternating current to transformer A will be cut off, and alternating current will be periodically supplied to this transformer through a front point of contact 8, contact 14 of code transmitter T, and the front contact 9 of track relay R^F, it being assumed that this latter relay is energized. The track relay, which is designated R^E₁, is of the alternating current type, and may, for example, be a centrifugal relay. The secondary of transformer 4 is connected with the input terminals of a full-wave rectifier 11, the output terminals of which are connected with the primary of a transformer 12. The secondary of the latter transformer is connected with the winding of the auxiliary polarized relay X. A condenser 13 may be connected across the primary of transformer 12 to smooth out the pulsations in the current supplied by the rectifier 11. Relay X is so connected with the transformer 4 that when the current in this transformer decreases, polar contact 10 will be swung to the right, whereas when the current in transformer 4

increases polar contact 10 will be swung to the left.

The operation of the apparatus shown in Fig. 2 will be apparent from the foregoing without detailed explanation.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a section of railway track, a track circuit including a track relay for said section, means including a normally de-energized device for supplying train controlling current to the rails of said section, a circuit for said device including a back contact of said track relay, a shunt for said circuit around said contact, and means receiving current from the connection between said relay and one track rail for closing said shunt before said relay contact closes when a train enters said section.

2. In combination, a section of railway track, a track circuit including a track relay for said section, means including a normally de-energized device for supplying train controlling current to the rails of said section, a circuit for said device including a back contact of said track relay, a shunt for said circuit around said contact, a transformer the primary of which is interposed between said track relay and one track rail, and means receiving current from the secondary of said transformer for closing said shunt before said relay contact closes when a train enters said section.

3. In combination, a section of railway track, a track circuit including a track relay for said section, means including a normally de-energized device for supplying train controlling current to the rails of said section, a circuit for said device including a back contact of said track relay, a shunt for said circuit around said contact, a transformer the primary of which is interposed between said track relay and one track rail, and a polarized relay receiving current from the secondary of said transformer for closing said shunt before said track relay contact closes when a train enters said section.

4. In combination, a section of railway track, a track circuit including a track relay for said section, means including a normally de-energized device for supplying train controlling current to the rails of said section, a circuit for said device including a back contact of said track relay, a shunt for said circuit around said contact, a polarized relay characterized by the fact that when it becomes de-energized its polar armature remains in the position to which it was last operated,

- a polar contact of said relay being included in said shunt, and a transformer the primary of which is interposed between said track relay and one track rail, and the secondary of which is connected with said polarized relay in such direction that increase of the current in the primary causes said polar contact to open and a decrease of the current in the primary causes said polar contact to close.
- 5 5. In combination, a section of railway track, a track circuit including a track relay for said section, means including a normally de-energized device for supplying train controlling current to the rails of said section, means for energizing said device when said track relay is open, and means receiving current from the connection between said track relay and one of the track rails for setting said device into operation before the track
- 10 relay opens when a train enters said section.
- 15 6. In combination, a section of railway track, a track circuit including a track relay for said section, means including a normally de-energized device for supplying train controlling current to the rails of said section, a polarized relay receiving current from the connection between said track relay and one of the track rails, and means for controlling said device jointly by said track relay and
- 20 said polarized relay.
- 25 7. In combination, a section of railway track, an alternating current track circuit including a track relay for said section, a transformer having its primary interposed between said track relay and one of the track rails, a rectifier connected with the secondary of said transformer, a second transformer the primary of which is connected with the output terminals of said rectifier, a polarized
- 30 relay connected with the secondary of said second transformer, and means controlled jointly by said track relay and said polarized relay for supplying train governing current to the rails of said section.
- 35 8. In combination, a section of railway track, a track circuit including a track relay for said section, an auxiliary relay receiving current from the connection between said track relay and one of the track rails and
- 40 characterized by the fact that it responds more quickly than the track relay to the entrance of a train into the section, and means controlled jointly by said track relay and said auxiliary relay for supplying train governing current to the rails of said section.
- 45 55 In testimony whereof I affix my signature.

GEORGE W. BAUGHMAN.
